UNITED STATES PATENT OFFICE.

WILLIAM T. SMITH AND JOSEPH FERGUSON, OF PHILADELPHIA, PA.

DESIGN FOR A RUG.

SPECIFICATION forming part of Design No. 15,383, dated September 2, 1884.

Application filed May 13, 1884. Term of patent 14 years.

To all whom it may concern.

Be it known that we, WILLIAM T. SMITH and JOSEPH FERGUSON, both of the city and county of Philadelphia, and State of Pennsylvania, have invented a new and original Design for Rugs, of which the following is a specification.

Our design is adapted to rugs in which borders extend around a center; and it consists in a border of parallel bars having thereon such ornamentation as is clearly shown in the accompanying illustration.

A represents the central part of the rug, shown as of a floral design.

15 The border consists, essentially, of two important parts, one of which comprehends the bars B and C, and the other bars D, E, and F. The main feature of the former is illustrated in the bar marked C, which consists of the two floral figures lettered G and H, forming the points of the scallops C', placed next to the bar B, and may have a few leaves, I, about said flowers. The bar B is shown as consisting of small scallops; but we do not deem that design essential, the said bar being narrow, and acts simply as a base-line upon which the bar C is laid off. In the latter of the borders—viz., D, E, and F—the bar F is the main feature, and consists of scallops or points J, which points or scallops have their points directed away from bars D and E, which, as in the case of the bar B, forms the base-line for said scallops. In large rugs these bars may consist of the semi-club-shaped figures K, and the bar E formed with a varie-

gated appearance; but in small rugs these bars are so narrow that they may be both combined into one variegated bar, the figures being too small to be recognized.

We do not claim that the figures separately 40 are new in themselves; but the said figures when combined and arranged as shown and described to form a design for rugs we consider novel.

We are aware of the patent to John Hamer, 45 No. 9,397, of 1876, and we do not claim anything therein shown.

Having now described our design, what we claim as new, and desire to secure by Letters Patent, is—

1. The design for a rug herein shown and described, the same consisting of a center bounded by a border, the essential feature of which is the floral figures G and H. 50

2. The design for a rug herein shown and described, the same consisting of a center bounded by a double border, one part of which is composed of the floral figures G and H, and the other or outer part of the border of the scallops or points J, the said borders being 60 separated from each other and from the center by bars forming base-lines. 55

In testimony of which invention we hereunto set our hands.

WM. T. SMITH.
JOSEPH FERGUSON.
